(57) **CLAIM**

The ornamental design for a pipe inspection camera, as shown and described.

DESCRIPTION

FIG. 1 is a front, right-side, top perspective view of a pipe inspection camera showing our new design;

FIG. 2 is a back, right-side, bottom perspective view of a pipe inspection camera showing our new design;

FIG. 3 is a front view thereof;

FIG. 4 is a back view thereof;

FIG. 5 is a right-side view thereof;

FIG. 6 is a left-side view thereof;

FIG. 7 is a top view thereof; and,

FIG. 8 is a bottom view thereof.

The broken lines in the drawings depict portions of the pipe inspection camera that form no part of the claimed design.
